UNITED STATES PATENT OFFICE

WALTHER ERICH, OF BERLIN-HALENSEE, GERMANY

BOX FOR FILING INDEX CARDS

Application filed January 29, 1929, Serial No. 335,928, and in Germany January 23, 1928.

Boxes for filing index cards have become known, so-called card indexes, which comprise a mechanism for selecting certain cards or card groups.

5 These mechanisms are not quite perfect as some of them allow only the selection of a limited number of cards or card groups and others do not even allow the selection of an individual card. The operation of such 10 mechanisms is also rather difficult and complicated.

This invention has for its object to provide a card index of simple construction, reliable operation and fulfilling all conditions, 15 so that the index cards to be mechanically selected, arranged at some distance from a side wall and from the bottom plate of the box and adapted to be shifted singly and in groups by means of selecting flaps or key rods 20 at two adjacent side edges by exterior selecting keys, are shifted on lower key rods by said side key rods, a further selection being possible by the lower key rods which effect the lifting of the selected index card. Pre- 25 determined cards of one or several groups selected by shifting, can be returned by auxiliary key rods into the initial position or can be secured in this position by locking bars to prevent movement when other cards are 30 shipped.

Several embodiment of the invention are illustrated, by way of example in the accompanying drawings in which:—

Fig. 1 shows in longitudinal section, the 35 simplest form of construction.

Figs. 2, 3 and 4 are similar views showing each a modification, the selecting possibility being increased by additional mechanisms.

Fig. 5 is a perspective view of a box for 40 filing index cards built according to the invention.

The several index cards have, besides the usual index tab *m* on the top edge, a laterally projecting tongue *a*, *b*, *c*, *d* . . . (Fig. 1) 45 indicating a main group, and downwardly projecting tongues 1, 2, 3 . . . on the bottom edge indicating a sub-group. The index cards are filed in a box *k* at a certain distance from the bottom plate of the box and from one side wall of the same. In the side wall

remote from the tongues *a*, *b*, *c*, *d*, auxiliary key bars *L'* are arranged, adapted to be operated from the outside of the box so that they can be made to penetrate into the gap between the side wall and the index cards. 55 In the side wall of the box adjacent to the tongues *a*, *b*, *c*, *d* . . . on the index cards, key rods *a'* *b'* *c'* *d'* . . . are arranged which are adapted to be operated from outside the box. Underneath the lower tongues 1, 2, 3 60 . . . key rods 1', 2', 3' . . . are arranged which, however, in the inoperative position are situated under the spaces between the lower tongues.

The selection of one or several main groups 65 of index cards is effected by means of the corresponding lateral key rods and tongues, for example in Fig. 1 the rod *b'* and the tongue *b*, by means of which the main group *B* of cards is shifted to the left a distance 70 *x*, corresponding to the spacing *x*, between the cards and the wall of the box at that side so that the lower tongues of the cards in this group are brought above the lower key rods. 75 To select from this selected main group the desired sub-group or sub-groups the corresponding lower key rods 3', 3' (two lower key rods being preferably provided for each sub-group) are lifted a distance *y*, whereby 80 from the selected main group those index cards are selected which have the lower tongues 3, 3; these selected cards being lifted so that they can be easily removed from the box.

By lowering the lower key rods the single 85 cards or sub-groups are returned into the initial position, and the main groups are returned into the initial position by the auxiliary key rods *L'* being pushed inward.

The number of the lateral and lower selecting tongues and key rods depends evidently on the actual conditions.

In the form of construction shown in Fig. 2 the lateral main group tongues *a*, *b*, *c*, *d*, *e* of the index cards *Q* bear against one of the side walls of box *K*, in which side wall the key rods *a'*, *b'*, *c'*, *d'*, *e'* to be operated from the outside are arranged. The opposite edges of the index-cards, spaced the distance *x* 95 from the corresponding side wall of the box, 100

have each an incision I, II, III, IV or V for the sub-groups, to which the key rods I' . . . V correspond. On the lower edge pairs of lifting tongues 1 to 5 are arranged adapted when shifted to the left to come into register with the lifting key rods 1' to 5'. In each of the two side walls and in the bottom plate of the box a pair of auxiliary key rods W', L' S' is further arranged designed to move simultaneously all of the cards of any actually collected group.

By these two selecting arrangements selection of single index cards or of groups of cards can be carried out in different manners.

15 The operations are as follows:

I. *Single selection*.—By shifting a key rod c' of the main group selectors for instance by depression of its key all cards of the corresponding group are brought into register with the pairs of lifting key rods 1— to 5—. By shifting a left key-rod for instance IV'—all other sub-groups are pushed back into their initial position and merely the cards of that 20 sub-group of the main group which have the incision IV remain above the lifting key rods. By operating a pair of the lifting key rods, for instance 1', the index card Q of the Sub-group IV of the main group c can be selected 25 by vertical parallel displacement.

II. *Sub-group selection*.—In this case the pair of auxiliary key rods S' is operated instead of the pair of lifting key rods 1' so that the entire Sub-group IV of the main group c 30 is lifted.

III. *Main group selection*.—After the operation of the main group key rod c' this whole group can be lifted out by means of the auxiliary rods S'.

40 IV. *Combined selections*.—By operating several main group keys corresponding sub-groups of different main groups can be brought into register with the pairs of lifting key rods corresponding. Sub-groups of all 45 main groups may be selected further by operating the auxiliary rods W' and corresponding single index cards of different sub-groups of all main groups may be selected by operating the corresponding key rods.

50 The selected index cards can be brought again all together by returning the auxiliary key rods S' into the lower position and shifted back all together into the initial position by operating the left-hand auxiliary key rods L'.

55 It will readily be observed that due to the number of selecting keys of each group, great accuracy may be obtained in selecting a card or cards. It is further possible to utilize also for the selecting, the upper card edge, by 60 mounting riders on the same.

For certain cases, it might be desirable to mechanically retain in their initial position predetermined cards which are not required. With this object in view incisions r', r² . . . 65 c⁵ are arranged in the lateral tongues a, b . . . of

the index cards as shown in Fig. 3. With these incisions r engage locking bars o', o² . . . which might be coupled in a convenient manner with the key rods a', b² . . . These locking bars o only release the incision r in the 70 tongues a, b, c of those cards which have to be moved by the catches so that only these cards can be shifted.

In the form of construction shown in Fig. 4 each card has at the point of the lateral edge 75 which stands opposite to the lateral tongues a, b . . . an incision a², b² . . . Each of the key-rods a', b' . . . is further coupled with a key rod a³, b³ . . . in the opposite side wall by means not shown in such a manner 80 that the two corresponding rods, move simultaneously into the box. In this manner only those cards can be positively shifted the key rod—for instance c'—of which is operated as all other index cards are retained in the initial 85 position by the counter catch c³ shifted at the same time.

Fig. 5 shows in perspective view a box for 90 filing index cards constructed according to the invention. In the front wall of the box the selecting keys z' z² for the lateral catches and z³ for the pairs of lifting key rods and further the auxiliary keys W, L, S for the corresponding auxiliary key rods are mounted.

95 I claim:

1. A box for filing index cards to be selected mechanically including means for mounting said cards in spaced relation to one side wall of the box and to the bottom plate of the same, said index cards having at least one tongue at two adjacent edges, in combination with lower key rods in said box, key rods in the side wall of the box corresponding to the side edge of the card having a tongue, said lateral key rods adapted to shift selected 100 cards over the lower key rods so that a further selection of cards can be lifted from said selected cards by said lower key rods. 105

2. In a box for filing index cards, as specified in claim 1, in combination with the selecting key rods in one side wall of the box, auxiliary rods in the opposite side wall of the box for returning the selected cards into the initial position.

3. In a box for filing index cards, as specified in claim 1, in combination with the selecting key rods in one side wall of the box, auxiliary key rods in the opposite side wall of the box for returning the selected cards into the initial position, and auxiliary key rods in the first-mentioned side wall of the box in which said selecting key bars are arranged whereby primary selection of cards of all the main groups may be effected and corresponding single index cards of different sub-groups of 115 said main groups may be selected. 120

In testimony whereof I affix my signature.
WALTHER ERICH.
